United States Patent Office

Des. 181,919
Patented Jan. 21, 1958

181,919

BOTTLE

Egmont Arens, New York, N. Y., assignor to Anderson,
Clayton & Co., Houston, Tex., a corporation of Delaware

Application July 30, 1957, Serial No. 47,154

Term of patent 14 years

(Cl. D58—8)

Fig. 1.

Fig. 2.

The dominant features of my design reside in the portions shown in full lines.

I claim:

The ornamental design for a bottle, as shown and described.
